UNITED STATES PATENT OFFICE.

CHARLES A. CULVER, OF NORTHFIELD, MINNESOTA, ASSIGNOR TO WIRED RADIO, INC., OF NEW YORK, N. Y., A CORPORATION OF DELAWARE.

MODULATION SYSTEM.

Application filed July 16, 1926. Serial No. 122,986.

My invention relates broadly to circuits for controlling the output of a high frequency electrical generator, and more particularly to a system of modulation for use in connection with radio telephone transmission or broadcasting.

One of the objects of my invention is to effect an improvement in the means whereby voice generated potentials may be made to control the high frequency output of a radio transmitter; and in particular to provide a system whereby the necessity for separate modulating and amplifying tubes is eliminated.

15 Another object of my invention is the suppression of harmonic frequencies in the high frequency power circuit of a radio transmitter.

A further object of my invention is to provide a circuit arrangement at a transmitter to secure greater over-all power efficiency in transmission.

Still another object of my invention is to provide a system of modulation for a transmitter whereby distortion is reduced to a minimum.

The invention will be more fully understood by reference to the following specification and accompanying drawing which shows 30 diagrammatically a wiring arrangement of a radio transmitter embodying the principles of my invention.

Referring to the drawing in detail the oscillator tube VT_3 , together with the associated inductance L_6 , capacitances C_5 and C_6 , and the plate potential supply B_2 , constitute a "master oscillator" or "driving circuit". Various forms of oscillator circuits may be employed.

40 The component parts consisting of the inductances L_2 , L_3 , L_4 , and L_5 , the capacitances C_1 , C_2 , C_3 , and C_4 , the triode tubes VT_1 and VT_2 , the plate potential supply B_1 , together with the usual filament supply, constitute a combined balanced amplifying and modulating system.

The transformer T , the microphone M , and battery B_3 constitute the means whereby sound waves are caused to control or modulate the energy delivered by the organization

to the antenna ground system 1—2 as shown through the coupling inductance L_1 .

High frequency energy from the master oscillator or driving circuit VT_3 is transferred to the amplifier-modulator circuit through 55 the inductive relation obtaining between the inductances L_6 , L_4 , and L_5 . The grids of the triodes VT_1 and VT_2 are thus subjected to a high frequency alternating potential. At any given instant the potentials of the grids 60 of these tubes will differ in phase by 180° . The resulting alternating current components in the two plate circuits will, therefore, be additive. However, the phase relation of the potentials on the grids due to certain harmonics in the input will be of such a nature that the resulting plate currents will nullify one another, and thus be suppressed. The energy of the purified high frequency current 65 thus existing in the inductances L_2 and L_3 70 is transferred to the antenna ground system through the inductive relation obtaining between L_1 , L_2 , and L_3 . In order to secure higher power efficiency, the output circuit of the amplifier-modulator tubes are adjusted 75 to resonance with the frequency delivered by the driving circuit. This is accomplished by means of the capacitances C_1 and C_2 . The input circuit of these tubes may also be adjusted to resonance with the driving circuit, 80 though this is usually unnecessary and, in fact, in most cases undesirable. The amplifier-modulator organization is less apt to oscillate in and of itself if the grid circuits are unturned.

85 Modulation is effected by means of the voice generated potentials developed in the secondary of the transformer T , said potentials being impressed on the grids of the tubes VT_1 and VT_2 simultaneously with the high 90 frequency potentials induced by the master oscillator. The audio potentials developed at the terminals of the secondary of the transformer T will be opposite in sign, that is, out of phase by 180° , and hence the grid of the 95 tubes VT_1 and VT_2 will be subjected to opposite audio potentials. As a result of this condition, the operating point on one of said tubes will be moving upward on its characteristic curve, while the operating point on the 100

other tube will be moving downward. This condition will result in an increase of output in one tube and a simultaneous decrease of output in the other tube of the balanced pair, 5 thus establishing a so-called push-pull condition in the output circuit of the tubes VT_1 and VT_2 . These audio potentials cause the operating point of the grids of the tubes to move up and down on their characteristic curves, 10 and thus the high frequency output of said tubes will be caused to vary in conformity with the voice generated potentials. As a result, the amplitude of the high frequency current developed in the antenna circuit will 15 vary in accordance with the audio frequency potentials impressed upon the grids of the modulator-amplifier tubes. It will thus be seen that modulation is effected without the use of separate modulating tubes, thus reducing 20 the operating cost and also securing a greater over-all power efficiency. Investigation has shown also that the over-all power efficiency is further increased as a result of the balanced arrangement of the modulator- 25 amplifier tubes as shown.

Because of the balanced arrangement of the tubes VT_1 and VT_2 , the voltage variations to which the grids of these tubes are subjected may readily be held within limits such 30 that the operating point on the characteristic curve will not pass beyond the straight portion of said curve, thus avoiding distortion which might otherwise result.

It is to be understood that modifications 35 may be made in the above described circuits without departing from the fundamental principles involved. For instance, a series 40 of tubes in parallel may be substituted for each of the single tubes VT_1 and VT_2 as shown, thus increasing the power output. Other and further modifications of the circuit 45 may be made within the scope of the appended claims without departing from the spirit of the invention.

What I claim as new and desire to secure by Letters Patent of the United States is as follows:

1. A signal transmission system comprising 50 a plurality of electron tubes each having grid, filament and plate electrodes, input and output circuits interconnecting said electrodes with the input and output circuits of one of said electron tubes mutually coupled for the generation of high frequency oscillations, a signal transmission circuit, and a pair of balanced circuits interconnecting others of said electron tubes and interposed between said signal transmission circuit and said high frequency oscillating circuit, and a microphone circuit including a transformer system having primary and secondary windings, with the secondary winding connected at opposite ends with grid electrodes of said electron tubes connected in said balanced circuits 55 for modulating the effects of said high fre-

quency oscillating circuit upon said signal transmission circuit.

2. A signal transmission system comprising a plurality of electron tubes each having grid, filament and plate electrodes, input and output circuits interconnecting said electrodes with the input and output circuits of one of said electron tubes mutually coupled for the generation of high frequency oscillations, a signal transmission circuit, a pair of said electron tubes being connected in balanced relationship with the output circuits of said tubes being connected in series, and the two input circuits being independently connected in series, a microphone circuit including a transformer system having primary and secondary windings, a connection between said primary winding and said microphone circuit and connections between opposite ends of said secondary winding and the grid electrodes of said pair of electron tubes, and connections between said high frequency oscillating circuit and the input circuits of said pair of electron tubes for impressing high frequency current thereon whereby the effects 90 of said current on said transmission circuit may be varied in accordance with the operation of said microphone circuit.

3. A signal transmission system comprising a plurality of electron tubes each having grid, filament and plate electrodes, input and output circuits interconnecting said electrodes, one of said electron tubes having inductances connected in its input and output circuits for sustaining high frequency oscillations, a pair of said electron tubes being connected in balanced relationship, a signal transmission circuit, connections between the output circuits of said pair of electron tubes and said signal transmission circuit, inductances in each of the input circuits of said pair of electron tubes, both of said inductances being coupled with the inductances in the output circuit of said first mentioned tube, a microphone circuit including primary and secondary windings with the secondary winding connected between the inductances in the input circuits of said pair of electron tubes whereby the effects of said high frequency oscillation circuit upon said transmission circuit may be variably controlled.

4. A modulation system comprising in combination a plurality of electron tubes each having grid, filament and plate electrodes, input and output circuits interconnecting said electrodes, connections between the input circuits of a pair of said electron tubes, connections between the output circuits of said pair of electron tubes, a signal transmission circuit, a connection between said last mentioned output circuits and said signal transmission circuit, another of said electron tubes having input and output circuits mutually coupled for the generation of oscillations and independently coupled with the input circuits 130

of said aforementioned electron tubes, means for adjusting the output circuits of said electron tubes to resonance with the driving frequency, and a voice control circuit connected with the circuits of said pair of electron tubes comprising a transformer system having primary and secondary windings, with the secondary winding connected at one end

with the input circuit of one of said pair of electron tubes, and at the opposite end with the input circuit of the other of the electron tubes of said pair for modulating the effect of said voice control circuit on said pair of electron tubes.

In testimony whereof I affix my signature.
CHARLES A. CULVER.
